UNITED STATES PATENT OFFICE.

BENJAMIN PAYEUR, OF WINONA, MINNESOTA.

TAKE-DOWN VAPOR-BATH CABINET.

1,144,861.

Specification of Letters Patent. Patented June 29, 1915.

Application filed August 3, 1914. Serial No. 854,798.

To all whom it may concern:

Be it known that I, BENJAMIN PAYEUR, a citizen of the United States, residing at Winona, in the county of Winona, State of Minnesota, have invented certain new and useful Improvements in Take-Down Vapor-Bath Cabinets; and I do hereby declare the following to be a full, clear, and exact description of the invention, such as will enable others skilled in the art to which it appertains to make and use the same.

This invention relates to hot air or vapor beds or baths, and has for its object the provision of a vapor-bath apparatus adapted for use in sanitariums and the like whereby a patient may be treated with medicated vapors or whereby a simple Turkish or Russian bath may be administered.

An important object is the provision of a bath cabinet which may be collapsed so as to occupy a minimum space for transportation or storage.

Another object is the provision of a device of this character provided with different accessories which may be interchanged for different purposes.

Another object is the provision of a device of this character which will be inexpensive to manufacture, easily set up and taken down, durable and rigid in use, quick in operation and a general improvement of the art.

With these and other objects and advantages in view, the invention consists in the novel construction, arrangement and combination of parts to be hereinafter more fully described and claimed, and illustrated in the accompanying drawing, in which,

Figure 1 is a side elevation of the device set up ready for use, Fig. 2 is a longitudinal sectional view therethrough, Fig. 3 is an end view, Fig. 4 is an elevation of the opposite end, Fig. 5 is a plan view of the supporting frame, parts being broken away; Fig. 6 is a cross sectional view through the frame.

Referring more particularly to the drawing, the supporting frame of my device comprises end bars 5 secured upon suitable legs 6. The sides of the frame comprise bars 7 secured upon the legs 6 and having hinged thereto other bars 8 as shown at 9, one pair of the bars 8 being rigidly connected with central legs 10 and the other pair being detachably connected with the legs 10. Staples

11 are secured upon the side members of the frame and are engaged by the hooked ends 12 of a transverse rod 13 which holds the sides in their proper spaced relation. Cleats 14 are secured upon the end bars 5 for reinforcing them and other cleats 15 are secured upon the side bars 7 and 8, the joints of the cleats being in staggered relation to the hinged joints 9, thereby bracing the sides of the frame and preventing them from buckling outwardly.

Upon one of the end bars 5 is secured a depending bar 16 provided with steps or teeth 17 engageable by a brace rod 18 hinged upon the bottom side of a head rest 19. Any suitable rubber pillow or the like 20 may be disposed upon the head rest 19 for the comfort of the patient.

The supporting bottom of the device comprises two slatted sections 21 which are similar in construction and which comprise cross bars 22 having a plurality of longitudinal slats 23 secured thereon. The ends of the transverse bars 22 are notched as shown at 24 for engagement with the cleats 14 and 15, whereby the slatted bottom is supported and at the same time the frame is prevented from collapsing inwardly.

In order to provide means for forming a bottom closure for the frame, I provide an apron 25 formed of rubberized cloth or other suitable material secured upon the lower portions of the sides and ends of the supporting frame by any suitable means which may be turn buttons 26 similar to the buttons used on automobile curtains, glove fastener clips or any other suitable devices. At its central portion the apron 25 is provided with a vent or opening 27 for a purpose to be described.

In order to provide a top closure for the frame, I provide a hood designated as a whole by the numeral 28, and which comprises a plurality of curved hoops 29 covered with rubberized fabric 30 which extends around the hoops, and also extends slightly below the ends thereof. The ends of the hood are closed by sheets of fabric 31 and 32, the end 32 being disposed at the head of the frame and provided with a cut-out portion 33 for a purpose to be described. The hood 28 is held upon the supporting frame by simply slipping it over the frame, the resilience of the hoops 29 holding the hood firmly. In order that the hoops 29

may be properly spaced apart, I provide a plurality of links 34 pivoted upon the hoops and pivoted to each other.

In order that dry or moist air, steam or any medicinal vapor may be supplied within the cabinet formed by the parts just described, I provide a pipe 35 extending through one end 5 and running longitudinally of the frame, the pipe being provided with perforations 36 at desired intervals. The pipe 35 is braced within the frame by means of a bracket 37 engaging the brace rod 13. The means for supplying heat or vapor into the pipe 35 may be of any desired form and construction, though in the present instance for the sake of illustration I have shown a stove 38 which may be oil, gas, electric or any other type. Any suitable receptacle 39 may be disposed upon the stove 20 for containing the liquid to be vaporized and supplied to the cabinet, the top of the receptacle 39 being connected by a pipe 40 with the pipe 35. If desired, a hood 41 which may be an ordinary heating drum, 25 may be disposed upon the stove 38 and connected with the pipe 35 by a pipe 42, thereby allowing dry air to be supplied to the cabinet, either alone or mixed with the vapor or steam from the receptacle 39.

30 The use of my device is as follows: The frame being set up as previously described, a sheet is laid upon the slatted bottom and a suitable pillow is placed upon the head rest 19. The patient to be treated is then placed upon the frame and the hood 28 is placed in the proper position over the frame, the patient's body being entirely covered by the hood and his head extending through the cutout portion 33 in the end 32 of the 35 hood. Steam, hot air, or any desired vapor is then supplied to the cabinet through the pipe 35 by means of the stove and receptacles previously described. The opening 27 in the apron 25 is provided for the escape of any 40 water formed by the condensation of steam within the cabinet.

45 When the device is not in use, the hood 28 is removed and the links 34 moved, whereupon the hood 28 may be collapsed with the 50 hoops 29 resting against each other, the hood consequently occupying but little space. The cross brace 13 is then disengaged from the staples 11 and the slatted sections of the bottom are removed. The frame may then be 55 separated where one pair of side bars 8 abuts

against the other pair of the side bars 8 which are secured to the central legs 10. Both pairs of side bars 8 are then folded outwardly upon the hinges 9 against the bars 7 secured to the legs 6, it being understood of course that the pipe 35 is first disconnected from the pipes 40 and 42 and from the frame. The parts being thus folded may be stored away in a small space. 60

From the foregoing description and a 65 study of the drawing it will be apparent that I have thus provided a novel and efficient cabinet whereby vapor or steam may be administered to a patient for medicinal or massage purposes, which is well adapted for 70 home or sanitarium use and which is simple and inexpensive.

It will be readily understood that I reserve the right to make various changes in the form, construction and arrangement of parts 75 of the frame and hood and to use any desired materials and furthermore to make such variations in the construction of the heating accessories as various requirements will dictate without departing from the spirit of 80 the invention or limiting the scope of the subjoined claim.

Having thus described my invention, I 85 claim:

A vapor bath cabinet comprising end bars, corner legs secured thereto, side bars connected with said legs, a pair of side bars hinged upon the free ends of one pair of said first named side bars and swingable outwardly thereon, another pair of side bars 90 hinged upon the free ends of the other pair of said first named side bars and carrying legs upon their free ends, cleats secured upon the inner faces of said end bars, other cleats secured upon said side bars and having their joints in staggered relation to said hinged joints and said second named legs, a transverse brace rod connected with said last named pair of side bars, a slatted bottom resting upon said cleats, an apron extending 100 across the lower portion of said frame, a hood extending over said frame and means for supplying vapor to the cabinet thus formed.

In testimony whereof, I affix my signature, 105 in the presence of two witnesses.

BENJAMIN PAYEUR.
